UNITED STATES PATENT OFFICE.

EMIL SCHLOSSBERG, OF NEW YORK, N. Y.

PIN-SETTER FOR BOWLING-ALLEYS.

1,080,373.

Specification of Letters Patent.

Patented Dec. 2, 1913.

Application filed May 19, 1913. Serial No. 768,513.

To all whom it may concern:

Be it known that I, EMIL SCHLOSSBERG, a subject of the Czar of Russia, and a resident of the city of New York, borough of Brooklyn, in the county of Kings and State of New York, have invented a new and Improved Pin-Setter for Bowling-Alleys, of which the following is a full, clear, and exact description.

10 My invention relates to a game known as tenpins, and has reference more particularly to means for centering the pins, which means comprise a plate or platform provided with openings for the pins and means for actuating the plate.

An object of the invention is to provide a simple and inexpensive pin setter which is formed of few and strong parts, none of which can easily get out of order.

20 Another object of the invention is to provide a pin setter which will indicate to the players that the pins are set in the proper places.

The invention consists of the construction 25 and combination of parts to be more fully described hereinafter and fully set forth in the claims.

Reference is to be had to the accompanying drawings forming a part of this specification, in which like characters indicate corresponding parts in all the views and in which:

Figure 1 is a plan view of an embodiment 35 of my invention; Fig. 2 is a section on line 2—2, Fig. 1; and Fig. 3 is a perspective view of the plate by means of which the platform is raised or lowered.

Referring to the drawings, 5 represents a platform, preferably made of wood fiber, 40 and provided with a plate 6, made of iron, constituting a backing for the fiber and preventing same from warping. The reason I use fiber is that ordinary wood after a little time, under the rolling action of the balls, 45 becomes worn out and requires frequent repairing. The platform 5 and the plate 6 are provided with ten openings 7 properly disposed according to the rules of the game. Engaging these openings are studs 8, also 50 preferably made of fiber, rigidly set into bed 9. The portion of the studs 8 projecting above the bed 9 is exactly equal to the combined thickness of the fiber piece 5 and the iron piece 6. That is, when the platform 55 rests on the bed 9 the upper surfaces of the studs 8 are flush with the upper surface of

the platform. The diameter of the openings 7 is slightly larger than the diameter of the base of the pin 10 used in the game. It is about equal to the diameter of the pin one-
60 eighth of an inch above the base.

The bed 9, which is in contour similar to the platform, is centrally provided with a recess 11, into which is fitted a plate 12 adapted to turn on the bolt 13 secured to the bed 9, substantially in the center of same and of the plate 12. The plate 12 is provided with a recess 14 for the head of the bolt 13, so that the head is substantially flush with the lower surface of the plate and the plate itself
65 with the head is slightly below the lower-most surface of the bed 9. The opposite or upper surface of the plate 12 is provided with recesses 15 adjacent the periphery of the plate, and also with inclines 16 leading
70 from the recesses to the upper surface of the plate.

The iron plate 6 is provided with vertical studs 17, the free ends of which carry balls 18 normally resting in the recesses 15 of the plate 12, that is, when the platform is resting on the bed. The plate 12 is provided with an arm 19 rigidly secured to the body of the plate 12 through the lateral surface of the same and by means of which the plate
80 85 can be turned on the bolt 13. When the plate 12 is turned in the direction indicated by the arrow in Fig. 3, that is, from the position shown in the dotted line in Fig. 1 to the position shown in full line in same figure, the incline 16 causes the studs 17 to rise, which necessarily forces the platform associated with the studs to rise, the platform being guided not only by the studs 17 but also by the studs 8 engaging the openings
90 95 95 of the platform.

When the platform is in position as shown in Fig. 2 the studs 8 are below the upper surface of the platform about an eighth of an inch. Thus the pins 10 can be placed on the
100 studs 8, being guided by the recesses formed between the upper surface of the platform and the studs. Then, by moving the arm 19 to the position indicated in dotted line of Fig. 1, the platform is lowered on to the bed
105 110 115 9, the pins remaining unmoved on the studs 8. The contact of the platform with the bed makes a positive support for the platform, so that the same cannot lag when the balls are rolling over the platform. The ball 18, positioned in the stud 17, is set in the stud so it cannot drop out from the end

of the stud, because when the platform is resting on the bed the ball 18 is slightly above the bottom of the recess 15 of the plate 12, for the purpose of giving a perfect support to the platform on the bed.

The bed 9, in the slot for the arm 19, is provided with electric contacts 20 leading to a bell or annunciator to indicate each new setting; not only for the purpose of control but also to indicate to the players that the platform has been raised from the bed. The contact 20 is operated when the arm 19 is in position indicated in Fig. 1, in full line. If the setter puts the pins on the platform and not in the recesses formed by the openings 7 and the studs 8, when the platform is lowered the pins on the same will come down with the platform, and the players will detect the movement of the pins, thus having a proof that the pins are not set in the proper place. The recesses formed by the pins 7 and the studs 8 afford a quick and easy placement for the pins; and, furthermore, the so-raised platform forms a guide for the pins on the studs 8 before the platform is lowered.

The bed 9, which carries the platform and the mechanism for raising and lowering the platform, is rigidly attached to beams 21, forming part of the alleys, and which carry the remaining framework of the alleys. As seen from the drawing, when the platform is resting on the bed 9 the frame 19 is located within the framework of the alleys, and is in no way exposed to injury by the balls or pins used for the play, nor are the other parts of the mechanism in any way exposed to strain when the game is played, as the plate 12 is then not carrying the load of the platform, which rests directly on the bed 9, as previously stated.

Having thus described my invention, what I claim as new and desire to secure by Letters Patent is:

1. In a device of the class described, a bed; studs on said bed, each adapted to

carry a pin; a platform comprising a fiber portion and a backing for said fiber portion, said fiber portion and backing having openings therein engaging said studs, and, normally, the upper surface of the platform being flush with the ends of the studs and supported by said bed; a rotatably mounted plate in said bed; and studs from said platform to said plate, said plate having means co-acting with said studs whereby said platform can be raised from said bed, thereby the openings in said platform forming recesses in combination with the studs substantially as set forth.

2. In a device of the class described, a bed; studs in said bed, each adapted to carry a pin; a platform having openings engaging said studs and normally resting on said bed; a plate in said bed, said platform having guiding means in said bed and in engagement with said plate; means for rotating said plate in said bed, said plate having means adapted to be engaged by the guiding means of the platform whereby the upper surface of the platform can be raised above the end of said stud, substantially as and for the purpose set forth.

3. In a device of the class described, a bed; studs in said bed, each adapted to carry a pin; a platform having openings engaging said studs normally resting on said bed; a plate having cam surfaces positioned in said bed; means extending from the platform to said cam surface of said plate; and means for rotating said plate from the outside of said bed whereby said platform can be raised above the end of said studs substantially as and for the purpose set forth.

In testimony whereof I have signed my name to this specification in the presence of two subscribing witnesses.

EMIL SCHLOSSBERG.
